UNITED STATES PATENT OFFICE.

CHARLES H. CLARK, OF WATERTOWN, WISCONSIN.

TILE-LAYING MACHINE.

1,112,894.

Specification of Letters Patent.

Patented Oct. 6, 1914.

Application filed September 21, 1912. Serial No. 721,556.

To all whom it may concern:

Be it known that I, CHARLES H. CLARK, a citizen of the United States, and a resident of Watertown, in the county of Jefferson and State of Wisconsin, have invented certain new and useful Improvements in Tile-Laying Machines; and I do hereby declare that the following is a full, clear, and exact description thereof, reference being had to the accompanying drawings, and to the characters of reference marked thereon, which form a part of this specification.

This invention relates to a novel machine for laying drain tile in the earth and to novel features of construction of the elements which go to make up the machine, and the invention consists in the matters herein-after set forth and more particularly pointed out in the appended claims.

20 A tile laying machine embodying my invention comprises a cavity forming mole having means to advance the same forwardly through the earth at a predetermined depth, with means to maintain a predetermined grade of the bottom of the cavity on which the tile are laid, and coöperating means to permit the wall of the cavity to set or become sufficiently permanent to hold its shape until the tile are laid therein. Connected to the mole so as to be drawn forwardly therewith through the cavity which is formed by the mole is a flexible tile carrier on which the tiles are laid one by one in endwise relation to each other whereby the tiles are drawn by the forward movement of the carrier into said cavity, and after a predetermined length of tile has been laid, depending upon the length of the carrier, the carrier is drawn forwardly from beneath the row of tile so as to leave the same in proper end to end relation.

In order to give the walls of the cavity formed by the mole such permanency as will maintain the proper cross section of the cavity and prevent the earth from falling back into the cavity before the tiling is laid, I provide between the cavity forming mole and carrier means to permit the walls of the cavity to set so as to prevent the same falling inwardly before the tile are placed. This may be effected by providing on the mole or other part associated therewith a gradually reduced supporting surface against or in contact with which the wall of the cavity gradually springs inwardly or sets, so as to

give to the inner surface of the wall a texture that will retain its shape and permanence until tiling is placed therein. This may be effected by tapering the rear end of the mole or by providing a following member, as an expansion block, which is rearwardly tapered to give proper support to the inspringing or contracting wall of the cavity. When a separate wall setting member is provided, it may take the form of an expansion block which follows the mole to expand the cavity beyond the mole diameter and thereafter allow the wall to contract within a period which depends upon the character of the soil in which the tile are being laid. When a separate expansion member is used it trails behind the mole and is made, in its greatest diameter, somewhat larger than the mole, for the double purpose of enabling one mole to be used with a number of sizes of blocks, and also to more firmly compact the earth laterally and upwardly, when working in a rather unstable character of earth, so as to thereby maintain the bottom of the cavity at the true predetermined grade while compacting the upper wall and the upper parts of the side walls of the cavity to prevent the earth falling into the cavity as before stated. The expansion and supporting surface may be formed on the mole member instead of a separately formed expanding member.

The reduction of the wall forming supporting surface, whether on the mole or a separate expansion block, permits a gradual contraction of the cavity wall as distinguished from a tendency of the wall to abruptly contract or spring inwardly if the wall supporting surface be abruptly discontinued. This gradual contracting or springing of the cavity wall gives a firm texture to the wall by what may be termed "smearing" action. Moreover, should pebbles or other particle like formations appear at the top wall of the cavity such "smearing" action will have the effect to embed the pebbles or like particles in the wall and prevent them dropping downwardly to the bottom of the cavity to interfere with the proper operation of the tile carrier and the proper laying of the tile.

The cavity forming mole is drawn through the earth by means of a narrow colter bar attached at its lower end to the mole and at its upper end, above the ground,

to a beam or like device which latter is suitably connected to a suitable power means for drawing the same forwardly, and is associated with means for manipulating the beam so as to maintain a predetermined grade of the bottom of the cavity regardless of the unevenness of the ground over which the draft device for the machine may be passing.

- 5 10 The tile carrier may, and preferably will, be made of a plurality of trough shaped articulated sections, the joining or articulation of the sections giving flexibility to the carrier to permit it to readily adapt itself 15 to indirect courses and also to be rolled for handling the same during transportation and storage. The trough shape of the carrier insures that the tile will seek its lowest 20 level on the carrier when supported thereby 25 and to direct the tile to the lowermost part of the floor of the cavity when the carrier is stripped therefrom, and thereby insure alinement of the tile in proper abutting relation to provide a continuous thoroughfare 30 of the maximum capacity of the tile.

35 Any suitable means may be employed for pulling the mole and the tile carrier forwardly through the earth and for stripping the carrier from a line of tile after the same 40 has been laid, practical forms of such means being hereinafter described.

45 In the drawings:—Figure 1 is a diagrammatic view illustrating a complete apparatus in operation. Fig. 2 is an enlarged view, 50 partially in elevation and partially in section, of the tile laying devices and the draft mechanism. Fig. 3 is a side elevation, with parts broken away, of the mole, expansion block and a portion of the carrier. Fig. 4 55 is a plan view of said parts. Fig. 5 is front end elevation of the expansion block. Fig. 6 is a cross section taken through the excavation formed by the mole, the expansion block and the tile carrier showing a tile 60 thereon. Fig. 7 is a side elevation of a modified form of mole and expansion member.

65 As shown in the drawings, 10 designates the cavity forming mole, 11 the expansion block and 12 the tile carried which trails 50 after and is connected to the expansion block.

70 13 designates a vertical colter bar which is attached at its lower end in any suitable manner to the mole 10 and extends upwardly 75 therefrom through a vertical opening 14 in the rear, thickened end of a draft bar 15, which latter is connected at its front end by a cable 16 to a pulling device, as the winch 17. For relatively light work this 80 winch may be a horse power winch, as herein shown. For heavy work I may employ a motor power winch. The front end of the draft beam 15 is suspended, in any suitable manner, from the axle 18 of a wheeled 85 truck, designated as a whole by 19. The said

90 colter is beveled or sharpened at its front edge, as indicated at 21, to facilitate its cutting through the earth.

95 The suspension means for the front end of the draft beam preferably comprise a 70 raising and lowering device, such as a screw or ratchet mechanism 22, the latter being herein shown, whereby the front end of the draft beam may be raised and lowered to maintain a predetermined grade of the tile 75 receiving cavity, notwithstanding irregularities of the ground over which the truck passes. In order to give stability to the truck relatively to the draft beam, I may connect the axle of the truck to the cable 80 16, at a point in front of the truck, by means of the cables 22' the latter acting in the manner of the hounds at the rear axle of a wagon.

100 The opening 14 in the rear end of the draft beam 15 is made wider in the plane of the beam, and is upwardly and outwardly tapered at its rear wall 23. The colter bar is held in the proper angular relation to the draft beam by engagement thereof with the 90 lower thickened portion of said rear wall 23 and blocks or wedges 24 between the upper end of the colter bar and the upper end of the forward wall 25 of said opening 14; the stress being transmitted from the 95 colter bar to the draft beam at said lower or thickened part of the rear wall of the opening 14 and said wedges or blocks 24. In order to adjust the machine for deeper or shallower cuts I may provide the colter bar 100 with a series of longitudinally spaced openings 28 to receive a transverse pin 29 on which the draft beam rests.

105 When the mole and the trailing parts are to be lifted out of the earth the blocks or wedges 24 are removed and a wider block or wedge (or a number thereof) inserted in its place, so as to force the bar against the rear inclined wall 23 of the opening 14, and thereby bring the colter bar at an acute angle to the draft beam. This adjustment has the effect to point the mole toward the surface so that when the machine is advanced the mole and the trailing parts are moved upwardly out of the ground. Should the 110 single adjustment not be sufficient to lift the mole out of the ground, the draft beam is dropped relatively to the colter bar, which is effected by the removal of the pin 29, and the blocks or wedges 24 again inserted into 115 place, which has the effect to decrease the angle of the partially raised colter bar to the draft beam and thereby increase the lifting effect on the mole. Moreover, the blocks or wedges 24 permit the angle of the colter bar 120 and mole to be varied in the normal use of the machine, so that when working in soft ground where the weight of the parts tends to depress or sink the mole, a slight upward 125 inclination given to the mole counteracts 130

such sinking tendency. When working in fairly firm earth, the mole may be maintained parallel with the draft beam.

The mole 10 is made of a cylindric body 5 of any suitable material and is beveled at its upper front side, as indicated at 31, so as to give a wedge effect to the front end of the mole to facilitate its entrance into and passage through the earth and compact the earth upwardly. The original contour of the cylindric shaped mole body is retained at its bottom, however, in order that the displacement of the earth by the mole shall be entirely upwardly.

15 The mole is shown as connected to the expansion block by means of a draft iron 32 which occupies a groove in the bottom of the block and is bolted thereto and is provided with an eye 36 to engage a hook at the 20 rear of the draft iron 37 which draft iron is apertured at its front end to receive a pin 38 that extends through the draft iron and through a bar 39 which extends rearwardly from and is attached to the mole, as shown 25 in Fig. 3. A tail iron 39' occupies a longitudinal recess in the expansion block at the bottom thereof beneath the draft iron 32 and overlaps the bar 39 and is apertured to receive the pin 38. The tail iron 39' extends 30 throughout the length of the expansion block and is rounded to conform to the lower curved side of the block, and is formed at its rear end with a hook 41 to engage an eye in a coupling piece 42 that is attached in any 35 suitable manner to the end of the carrier 12. This construction permits an expansion block to be readily lifted from the tail iron 39', to be replaced by a larger or smaller block. Moreover, the pull from the mole to 40 the carrier is transmitted through the tail iron and not through the expansion block.

The mole is made of a diameter somewhat greater than the tile to be laid. For instance, when laying a four inch tile, which is about 45 five and one-half inches in external diameter, a mole of about seven inches diameter will be employed. The expansion block, when the latter is employed as a separate part, is made at its largest diameter, as indicated at 42, of somewhat larger diameter than that of the mole. For instance, in the 50 dimensions above given I may employ an expansion block of about eight inches maximum diameter. The maximum diameter of 55 the expansion block will depend largely on the character of the earth in which the tile is being laid, it being evident that a larger expansion block, and a greater extent of expansion of the earth relatively to the diameter of the mole, may be employed in soft moist earth than in harder and more solid earth. The said expansion block is tapered on its upper and lateral sides at the front end, as indicated at 43, 44, 44, said tapers 60 preferably extending throughout the prin-

cipal length of the block. These tapers are carried to the front end of the block to about one-half the diameter thereof, as indicated in Fig. 3. The tapers 44, 44 at the lateral sides of the front end of the block are preferably less than the top taper so that the expansion pressure imparted to the wall of the cavity, as the expansion block moves through the cavity, is partially sidewise, but principally upwardly. No expansive pressure is exerted on the bottom or floor of the cavity by reason of the fact that the front end of the block is maintained in line with the mole, which latter bears a fixed relation to the draft beam 15 thereof. The 70 walls of the cavity are compacted at the lateral and upper sides thereof in a manner indicated by the crescent shaped darkened portion 46 in Fig. 6. The said expansion block is also tapered from the greatest diameter 42 thereof on its top and lateral sides to its rear end, as indicated at 47, 48, 48, the top taper 47 being preferably somewhat greater than the side tapers 48, 48. As a result of this tapered form given to the rear end of 75 the expansion block, the walls of the cavity, after they have been expanded by the block, follow and are supported by the tapered portion of the rear end of the block and are, therefore, allowed to contract gradually inwardly at the top and lateral sides of the cavity, and in so contracting over the tapered portions of the block the surfaces of the contracting walls are "smeared" and given a compact texture which prevents the 80 walls caving or falling inwardly, which would occur if the block terminated abruptly at its largest diameter.

Referring now to the tile carrier and to the improvements therein constituting my 105 invention, the said carrier is herein shown as composed of a plurality of relatively short sections 50, 50, there being preferably two or more sections for the length of each tile A laid thereby. These sections are of trough shape, and open upwardly to receive the tile. They are made of a radius to extend at their sides about one-half way up the sides of the tile, as shown in Fig. 3. The said sections are connected together by means of 110 one or more strips 51 which lie over the central inner sides of the sections and said strip may be attached to the sections by any suitable fastening means, as by the rivets 52. The sections overlap each other at adjacent 115 sides, and are preferably overlapped at their lower central parts to a slightly greater extent than at their sides, as shown in Fig. 4. The forward end of each section lies over the rear end of the next front section, as 120 indicated in Figs. 3 and 4, so as to present no obstructions at the joints to dig into the floor of the cavity. The straps or bands 51 preferably possess considerable flexibility, and constitute, in effect, hinges for connect- 125 130

ing the sections of the articulated carrier thus constructed so that the carrier is free to adapt itself to indirect courses when being inserted into the cavity, and also to be readily rolled for storage and transfer purposes. This form of the carrier permits the carrier to readily follow the cavity that is curved or deflected laterally out of a straight line. This due to the fact that the carrier, 10 as a whole, possesses considerable lateral flexibility and, furthermore, by reason of the curvature of the lower sides of the carrier sections, said carrier may, to an extent, roll or turn laterally in the cavity in passing about a curve.

An advantage of the trough shaped carrier shown is that the tiles are thereby maintained centrally within the cavity, so that when the carrier is pulled away or stripped 20 from the tile they naturally fall to the lowest point of the cavity and are thereby aligned. Owing to the friction between the carrier and the tile, when the carrier is stripped away from the tile, the tile will be 25 forced into close abutting relation so as to thereby avoid wide joints between the adjacent tiles.

In order to strip the carrier from the tile after a row of tile, the length of the carrier, 30 has been laid, an excavation, such as is shown at 55 in Fig. 2, is dug into the ground to uncover the forward end of the carrier. Preferably the carrier sections terminate short of the forward ends of the 35 strap or bands 51 and the excavation 55 is dug between the first tile of the row and the rear end of the expansion block. After the excavation has been dug, an open strut frame 56 is interposed between the end of 40 the forwardmost tile on the carrier and the opposite wall of the excavation. Thereafter as the mole and the expansion block and the carrier are moved forwardly and the row of tile in rear of the strut frame 56 is 45 held from moving by said frame so that the carrier is pulled away from beneath the laid row of tile to allow the tile to drop upon the floor of the cavity. As the carrier is thus pulled away from the row of laid 50 tile, thus held from movement, other tiles are placed upon the carrier, to be thereby carried into the next section of the cavity. The space between the two rows of tile thus laid, and which occurs at the bottom of the 55 excavation 55, is filled in by the number of tiles or parts of tiles required to bridge said space. After the next succeeding row of tiles has been laid another excavation, at the forward end thereof, is dug, and the tile carrier 60 is stripped from said row and another row of tiles is commenced in the same manner as before set forth.

In starting a tile receiving cavity it is convenient and preferable to begin at the 65 outlet end and work backwardly. If this

outlet end is an open ditch or the like, the carrier may be very conveniently manipulated to start the same into the cavity. Where the line of tiles begins where there is no natural outlet, as for instance, at the beginning of a branch or lateral, an excavation of suitable size will be required to be dug to enable the carrier to be drawn freely into the cavity as the mole advances.

The operation of the tile laying apparatus 75 will be apparent from the foregoing. In such operation the tile are laid continuously on the carrier as the carrier advances and are drawn thereby into the cavity. During the advance of the mole to form the cavity 80 the grade of the cavity is maintained at a predetermined angle or fall by the coöperation of a surveyor in rear of the draft device using a surveyor's level or like instrument, and a person at the front end of the 85 draft beam whose duty it is to raise and lower the front end of the draft beam in accordance with signals communicated to him by the person at the surveying instrument.

Instead of providing a separate expansion block, as described, I may construct or shape the rear end of the mole to function as an expansion element, or to function as a supporting element for the inwardly springing or contracting wall of the mole to "smear" the wall of the tile receiving cavity. Such a device is shown in Fig. 7. In this device the front end of the mole and its connection with the colter bar is the same 90 as shown in the previously described figures. At its rear end it is provided with a portion of enlarged diameter 60 and in rear thereof with top and lateral tapered portions 61, 62 which serve the same purposes as the tapered 100 portions 47, 48 of the expansion block before described.

It is obvious that my invention is capable of further variation within the spirit and scope of the broader claims appended hereto 110 and the invention is not limited to the structural details enumerated, except as herein-after made the subject of specific claims, and as imposed by the prior art.

I claim as my invention:—

1. In a tile laying machine, a mole with means to advance it through the earth, associated with an expansion and smearing member at the rear end of the mole, said member being made of greatest diameter adjacent to its rear end and tapered at its top and sides from its greatest diameter thereof toward the rear end, and longitudinally straight and transversely cylindric at its lower side, with tile laying means.

2. In a tile laying machine, a mole, with means to advance it through the earth, and an expansion block connected to the rear end of the mole, said block being made of greatest diameter near its rear end and tapered

115

120

125

130

at its top and side from its greatest diameter to both its front and rear, and made cylindric at its bottom.

3. In a tile laying machine, a mole, with means for advancing it through the earth, an expansion block in rear thereof, a tile carrier in rear of the expansion block, and a strap inset into the lower side of the expansion block and having means at its ends to connect it with the mole and carrier, respectively.

4. In a tile laying machine, an expansion block which is tapered at its top and lateral sides from the intermediate largest diameter thereof toward its rear end and is longitudinally straight and transversely cylindric at its bottom.

5. In a tile laying machine, an expansion block which is tapered at its top and lateral sides from the intermediate largest diameter thereof toward its rear end, said block being also tapered at its top and sides from said intermediate largest diameter toward its front end, and being longitudinally straight and transversely cylindric at its bottom.

6. In a tile laying machine, a mole, with

means for advancing it through the earth, and tapered wall forming or smearing means at the rear of the mole over which the cavity wall gradually contracts, the taper of such means acting on the upper and side walls of the cavity and said means being longitudinally straight and transversely cylindric at its bottom to give definite cylindricity to the floor of the cavity.

7. In a tile laying machine, a mole, with means for advancing it through the earth, an expansion block in rear of the mole, a tail iron inset into the lower side of the block, a tile carrier attached to the rear end of the tail iron, said block being removable from the tail iron and having means at its front end to connect it to the rear end of the mole.

In testimony, that I claim the foregoing as my invention I affix my signature in the presence of two witnesses, this 13th day of September, A. D. 1912.

CHARLES H. CLARK.
